UNITED STATES PATENT OFFICE.

EDWARD B. JACOBSON, OF PITTSFIELD, MASSACHUSETTS, ASSIGNOR TO J AND B MANUFACTURING COMPANY, OF PITTSFIELD, MASSACHUSETTS, A CORPORATION OF MASSACHUSETTS.

LIGHTING SYSTEM.

1,102,194.

Specification of Letters Patent. Patented June 30, 1914.

Application filed May 2, 1912. Serial No. 694 681.

To all whom it may concern:

Be it known that I, EDWARD B. JACOBSON, a citizen of the United States, residing at Pittsfield, in the county of Berkshire and State of Massachusetts, have invented certain new and useful Improvements in Lighting Systems, of which the following is a specification.

My present invention relates to lighting systems and particularly to lighting systems employed in connection with motor vehicles.

Such systems are usually operated by means of a magneto generator as the source of electrical energy, producing an alternating current, and include one or more incandescent lamps, which are controlled through the medium of a switch. In previous known forms of like systems certain material objections are to be noted, namely, the lamps are placed in series in the same circuit, whereby the use of one lamp involves the operation of all and the opening of the circuit extinguishes all; further, the operation of the engine at low speeds fails to operate the lamps; and lastly, the absence of means for controlling and regulating the energy from the source of current whereby a substantially constant voltage at the lamps is effected irrespective of engine speed.

To remedy these objections constitutes the essential object of my present system.

The foregoing and other objects I accomplish by means of a lighting system for motor vehicles which comprises as its essential features a magneto generator or other suitable source of alternating-current energy, one or more incandescent lamps, each lamp being placed in a separate circuit or otherwise capable of operation independently of every other lamp, an impedance or choke coil or other equivalent means in circuit with the source of current and adapted to maintain an approximately constant current in the circuit, and a switch interposed in each lamp-circuit.

I will proceed to describe a specific useful form of embodiment of my invention, in connection with the accompanying drawings, wherein—

Figure 1 is a vertical sectional view of an impedance coil constructed in accordance with the objects of my invention; Fig. 2, a top view of the base of the coil; and Fig. 3, a diagrammatic plan view of a lighting sys-

tem constructed and arranged in accordance 55 with my invention.

The impedance coil herein shown comprises a base 1, core magnets 2, 2, mounted on the base 1 and arranged in parallel, coils or windings 3, 3, carried by the cores 2, 2, 60 casings 4, 4, mounted on the base 1 and surrounding the coils 3, 3, and suitable terminal facilities 5, 5, 6, providing a common feed connection and separate ground connections for the coils.

The base 1 is shown as a plate, preferably circular in form and constructed of magnetic metal, having suitable marginal lugs 7, 7, for connection with a support, and provided on its upper face with spaced recesses 8, 8, into which the lower ends of the casings 4, 4, are fitted. Seated in recesses 9, 9, provided in the base centrally of the recesses 8, 8, are shown upright metallic cores or magnets 2, 2, preferably formed of a bundle 70 of soft-iron wires, extending upward into the casings 4, 4. Mounted on the cores 2, 2, and preferably disposed about the upper ends thereof are shown separate windings 3, 3, having their lower leads 10, 10, extending 80 down through suitable openings 11, 11, extending laterally from and communicating with a recess 12 provided in the under side of the base, the leads 10, 10, being connected to a common terminal 6 provided in said recess 12 and extending upward through a suitable aperture in the base to form a binding-post on the upper face of the base from which it is suitably insulated.

The casings 4, 4, are shown as upright 90 cylinders which are open at their lower ends and are closed at their upper ends by suitable insulation disks or plates 13, 13, disposed freely over the cores 2, 2. Mounted on the disks 13, 13, are shown the terminals 95 5, 5, in the form of binding-posts, to which the leads 14, 14, at the upper ends of the windings 3, 3, are respectively electrically connected.

While I have preferred to construct the 100 base 1 of magnetic metal, such as soft iron, to provide an air-gap between the upper ends of the cores 2, 2, and to arrange the windings in such manner that adjacent ends of the cores 2, 2, are of like polarity, these 105 features I do not claim as essential to the operation of the system. Modifications thereof may be made by the provision of a

closed magnetic circuit or endless core, by variations in the number of turns in the windings, by arranging the windings so that the adjacent ends of the cores have like poles, or otherwise, but I have found by experimentation that the construction herein shown is productive of greater efficiency.

In the arrangement of the system, the lamps 17 are each placed in a separate circuit with the source of current 15, having separate ground connections and a common feed connection at the switch 16. Between the switch 16 and the lamps 17, I interpose in the separate lamp circuits 18, 19, an impedance coil common to both circuits, and which preferably comprises separate adjacent cores 2, 2, on which respective windings 3, 3, are placed for separate connection with the circuits 18, 19, the cores being magnetically closed by a yoke or base 1 at one end and open at the opposite end, thereby providing an air-gap. Assuming the engine to be running and the switch 16 to be closed in both circuits, the current generated at 15 flows through the windings 3, 3, and the lamps 17, 17, setting up a reactance in the impedance coil which regulates the current and maintains an approximately constant voltage at the lamps. The current generated at 30 at the source of current usually has a voltage largely in excess of that required for the operation of the lamps, and, unless reduced, would burn them out. Moreover, this voltage is variable, increasing with the speed of the engine. An essential feature, therefore, of the present system is the introduction into the circuit of an impedance coil producing a reactance in the circuit and which varies approximately proportionately to the frequency of current alternations, maintaining a substantially constant current in the circuit. In previous known systems, the absence of similar controlling means causes the lamps to largely vary in 45 illuminative strength, rising or falling with the voltage in the circuit, and finally to

flash out as the speed of the engine increases to a maximum.

By means of the several lamp circuits and a switch for controlling each circuit independently of the other, one of the circuits may be opened or closed during the operation of the other circuit and without affecting the normal operation of the impedance coil in the circuit in use.

It may be further observed that I do not limit myself in the present system to the use of any particular number of lamps at one time, as the number may be increased indefinitely within the limits of the capacity in the source of current, providing, however, that a separate circuit including an additional magnetic core and separate winding thereon be added for each additional lamp employed.

The present system is designed to obviate the necessity of using a separate magneto generator exclusively for lighting purposes, as it is adapted to include the source of electrical energy for ignition purposes as a source of energy for the operation of the lamps, on vehicles employing a magneto generator.

I claim:—

The combination with a lighting system of the class described and including a source of alternating current having a variable voltage, and a plurality of incandescent lamps in circuit with the source of current and arranged in multiple, of an impedance coil having a plurality of cores, and separate windings on each of the cores having a common feed connection and separate ground connections, each of the windings being in circuit with a separate lamp.

In testimony whereof I hereto affix my signature in presence of two witnesses.

EDWARD B. JACOBSON.
